UNITED STATES PATENT OFFICE.

PATRICK J. MAGUIRE, OF SALEM, ASSIGNOR OF ONE-HALF TO EDWARD J. STEWART, OF MILLIS, MASSACHUSETTS.

APPARATUS FOR CHARGING LIQUIDS WITH GAS.

SPECIFICATION forming part of Letters Patent No. 552,482, dated December 31, 1895.

Application filed March 25, 1895. Serial No. 543,018. (No model.)

To all whom it may concern:

Be it known that I, PATRICK J. MAGUIRE, of Salem, in the county of Essex and State of Massachusetts, have invented certain new and useful Improvements in Apparatus for Charging Liquids with Gas, of which the following is a specification.

This invention has for its object to provide a simple and effective machine for charging a liquid with gas and for delivering the charged liquid to bottles or other receptacles; and it consists in the improvements which I will now proceed to describe and claim.

Of the accompanying drawings, forming a part of this specification, Figure 1 represents a side elevation of a machine or apparatus embodying my invention. Fig. 2 represents a sectional view of the same, the supporting-standard being broken away. Fig. 3 represents a side view of a portion of the apparatus from the side opposite that shown in Figs. 1 and 2. Fig. 4 represents a section on line 4-4, Fig. 5. Fig. 5 represents a perspective view of the mixer and its connections.

The same letters of reference indicate the same parts in all the figures.

In the drawings, *a* represents a cylinder having an inlet-pipe *b*, which receives liquid from a liquid-supply pipe *c* and gas through a gas-supply pipe *d*, the gas being under pressure.

e represents a piston which is reciprocated in the cylinder by suitable means, such as a crank-shaft *e*, journaled in bearings in the supporting-standard *f* and a rod or pitman *e*² connecting the crank-shaft with a cross-head *e*³ to which the piston-rod is attached.

g represents a by-pass connecting the ends of the cylinder and connected at its upper end with a mixer in the upper portion of the cylinder. Said mixer comprises an annular chamber *h*, communicating with the by-pass *g* and provided in its periphery with numerous small discharge outlets or perforations through which the liquid and gas enter the outlet end of the cylinder, and another annular chamber *p*' connected with a gas-supply pipe *p* and separated from the chamber *h* by a wall *p*² having numerous small perforations, Fig. 4. When the piston rises in the cylinder a mixture of liquid and gas enters the lower portion

through the inlet *b*, filling the cylinder below the piston. When the piston descends the mixture of liquid and gas accumulated below it is transferred through the by-pass *g* and mixer to the upper portion of the cylinder, this result being due to the direct pressure of the piston on the mixture below it and to the suction in the cylinder above the piston caused by the downward movement of the latter. The liquid is minutely subdivided by passing through the perforations of the mixer and is therefore intimately mixed and charged with the accompanying gas. When the piston next rises the accumulation of gas and liquid, or, more properly, the gas-charged liquid, above the piston is forced through an outlet-pipe *i* extending from the top of the cylinder, it being prevented from returning through the by-pass *g* by a check-valve *g*² therein, the outlet-pipe *i* having a check-valve *i*² which prevents the return of gas and liquid to the cylinder when the piston is descending.

The pipe *p* communicating with the chamber *p*' of the mixer extends to the interior of a reservoir *j*², which receives the gas-charged liquid, as hereinafter described. A portion of the gas in the reservoir *j*² enters the chamber *p*' through said pipe and passes in numerous small streams into the liquid in the chamber *h*. The said gas acts to charge and subdivide the liquid within the mixer before it is additionally subdivided and charged by its passage through the orifices of the mixer, as above described.

It will be seen that the perforated wall *p*² constitutes a considerable part of the inner surface of the chamber *h*. Hence the liquid entering said chamber is disposed so that the gas from the chamber *p*' is uniformly diffused through said liquid.

The pipe *p* is provided with a check-valve *p*², which prevents an outward flow of gas and liquid from the cylinder through said pipe.

The outlet-pipe *i* communicates with the upper portion of a casing *j*, which is vertically arranged and is subdivided by a partition *j*³ into two chambers *j*' *j*², the former being a primary reservoir and the latter a secondary reservoir. The partition *j*³ has a stand-pipe *k*, communicating with the lower chamber *j*², 100

and a casing k' inclosing said stand-pipe and closed at its upper end, said casing having openings k^2 k^2 below the upper end of the stand-pipe. The charged liquid entering the 5 chamber j' is further subdivided by passing through a perforated plate or strainer m and is further charged with the gas which accumulates in the said chamber. The charged liquid is transferred, as hereinafter described, 10 to the chamber j^2 , which is the reservoir from which the liquid is drawn into bottles, said chamber having at its lower end a nozzle j^4 , adapted to deliver the charged liquid to a bottle or other receptacle.

15 The supply of liquid to the cylinder a is automatically regulated by means of a cock o in the liquid-supply pipe c , a float o' in the secondary reservoir, and suitable intermediate connections whereby the float in rising closes 20 the cock and shuts off the supply of liquid from the cylinder and in falling opens the cock and admits liquid to the cylinder, said connections, as here shown, comprising a rock-shaft o^2 , journaled in a packed bearing in the 25 wall of the secondary reservoir, arms o^3 o^4 on said rock-shaft, and rods o^5 o^6 connecting said arms respectively to the float o' and to the lever o'' on the cock o .

The stand-pipe k and casing k' constitute a 30 trap for controlling the movement of the liquid from the primary reservoir j' to the secondary reservoir j^2 by differences between the gaspressures in the two reservoirs. It is desirable to limit the accumulation of liquid in the 35 secondary reservoir j^2 and prevent said reservoir from being filled with liquid, in order that an accumulation of gas may be present in said reservoir to act, as described, in the mixer, and in order that the float o' may be 40 free to operate to close the liquid-supply pipe when the predetermined quantity has been accumulated. It will be seen that the stand-pipe and casing enable an excess of gas-pressure in the secondary reservoir over that in 45 the primary reservoir to prevent the flow of liquid into the secondary reservoir, and that when the gas-pressure in the primary reservoir exceeds that in the secondary reservoir the liquid is forced through the trap until the 50 gas accumulates in the secondary reservoir sufficiently to again prevent the downward flow.

A sufficient supply of liquid in the cylinder to lubricate the piston when the liquid-supply pipe is closed by the float o' is insured by the pipe p , which extends downwardly into the lower portion of the reservoir j^2 , so that its lower end is submerged in the liquid when the latter accumulates to any considerable extent, as when the operation of bottling is temporarily suspended, so that when the piston descends it draws or pumps a supply of liquid from the reservoir through the pipe, thus lubricating the piston and the inner surface of 60 the cylinder. The pipe p also enables all or nearly all the liquid that finds its way to the

reservoir j^2 to be returned to the cylinder by the described pumping action of the piston, so that if a quantity of imperfectly-charged liquid is present in the reservoir it may be 70 charged by returning it to the cylinder, the liquid-supply pipe c being shut off by the action of the float o' , so that only gas is admitted at the inlet of the cylinder.

It will be seen that the construction above 75 described constitutes a simple and effective self-regulating or automatic liquid-charging apparatus, having ample provisions for thoroughly charging the liquid and provided with 80 means for storing the charged liquid without loss of pressure and for stopping the charging operation before an excessive quantity can be accumulated. Hence no attention is required on the part of the operator to prevent an over-accumulation of the charged liquid, the provision for lubricating the cylinder enabling the piston to operate continuously without detriment whether the charging operation is 85 going on or not.

I claim—

1. A liquid-charging apparatus comprising a cylinder having an inlet at one end and an outlet at the other end, a by-pass connecting said ends, and a mixer communicating with the by-pass in the outlet end of the cylinder. 90

2. A liquid-charging apparatus comprising a cylinder having an inlet at one end and an outlet at the other end, a by-pass connecting said ends, a mixer communicating with the by-pass in the outlet end of the cylinder, a 100 storage reservoir communicating with the outlet end of the cylinder, and a connection between the storage reservoir and the mixer whereby gas from the reservoir is admitted to the mixer.

3. A liquid-charging apparatus comprising a cylinder having an inlet at one end and an outlet at the other end, means for mixing gas and liquid admitted to the cylinder and for ejecting the mixture through the outlet, a primary reservoir communicating with the outlet, and a secondary reservoir having a 110 trapped pressure-controlled inlet communicating with the primary reservoir.

4. A liquid-charging apparatus comprising 115 a cylinder having an inlet at one end and an outlet at the other end, a by-pass connecting said ends, a liquid chamber within the cylinder communicating with the by-pass and provided with numerous small outlets or perforations, a gas chamber communicating with the liquid chamber through numerous small outlets or perforations, a storage reservoir communicating with the outlet end of the cylinder, and a connection between the storage reservoir 120 and the gas chamber whereby gas from the reservoir is admitted to said gas chamber.

5. A liquid-charging apparatus comprising a cylinder having an inlet at one end, an outlet at the other end, means such as the piston, 125 by-pass, and mixer for mixing gas and liquid admitted to the cylinder, a reservoir communi-

cating with the cylinder outlet, a float in the reservoir, a cock controlled by said float and adapted to control the admission of liquid to the cylinder, and a gas or liquid returning pipe connecting the reservoir with the cylinder.

5 In testimony whereof I have signed my

name to this specification, in the presence of two subscribing witnesses, this 22d day of March, A. D. 1895.

PATRICK J. MAGUIRE.
